PETER A. WILLIAMS, OF WHITE PLAINS, NEW YORK, ASSIGNOR TO INGERSOLL-RAND COMPANY, OF JERSEY CITY, NEW JERSEY, A CORPORATION OF NEW JERSEY

BLOWING DEVICE

Application filed August 14, 1929. Serial No. 385,886.

This invention relates to rock drills, but more particularly to a blowing device for fluid actuated rock drills of the hammer type.

One object of the invention is to assure an abundant supply of pressure fluid to the drill hole for removing the cuttings therefrom.

Another object is to assure a sealed connection between the hollow working implement and the source of pressure fluid supply during the blowing period, thus avoiding leakage of pressure fluid through the forward extremity of the rock drill.

Still another object is to avoid contact between the conduit through which pressure fluid is supplied and the working implement during the normal operation of the drill.

Other objects will be in part obvious and in part pointed out hereinafter.

The figure in the drawing is a sectional elevation of a rock drill equipped with a blowing device constructed in accordance with the practice of the invention.

Referring more particularly to the drawing, A designates generally a rock drill comprising a cylinder B provided with a piston chamber C and having free exhaust ports D to afford communication between the piston chamber and the atmosphere.

Disposed in the piston chamber C is a reciprocating hammer piston E having a forward extension F which extends slidably through a front cylinder washer G at the front end of the cylinder B and is provided with longitudinal flutes H for engagement with ribs J carried by a chuck K. The chuck K may, as illustrated, abut with its rearward end the forward end of the front cylinder washer G and is disposed rotatably within a front head L preferably centralized with respect to the cylinder B by the front cylinder washer G.

The chuck K may be of a well known type having a bore O to receive and guide a working implement, such as a drill steel, only the rearward end or shank P of which is shown. The working implement P has the usual bore Q to convey cleansing fluid to the bottom of the hole being drilled.

In the rearward end of the cylinder B is

an enlarged bore R for the accommodation of rotation mechanism comprising a ratchet ring S and the head T of the rifle bar U having flutes V for interlockingly engaging ribs W of a rifle nut X threaded in the rearward end of the piston E. The head T of the rifle bar may carry the usual spring pressed pawls (not shown) adapted for engagement with introverted teeth Y carried by the rotation ring S for imparting rotary movement to the piston and thus also to the working implement P through the medium of the chuck K.

In the rearward and forward ends of the rotation ring S are formed annular chambers Z and b respectively, connected in this instance by supply passages c, also in the rotation ratchet S. The annular chamber Z serves as a supply reservoir, and the chamber b as a valve chamber to accommodate an annular plate type distributing valve d adapted to control inlet passages e and f leading from the chamber b to the rearward and forward ends respectively of the piston chamber C. A closure is provided for the front end of the chamber b by a back cylinder washer g wherein are formed the passages e and f and which also acts as a closure for the rearward end of the piston chamber C.

Disposed at the rearward end of the cylinder B is a back head h which preferably seats on the rotation ratchet S and may be clamped in the operative position with respect to the cylinder B in any suitable manner. By seating the back head on the rotation ratchet S said back head forms a closure for the rearward end of the supply reservoir Z and in this instance also acts as a housing for a throttle valve j having a central chamber k into which pressure fluid may be constantly admitted from a source of supply (not shown) and in the side of the throttle valve is a port o adapted to register with a passage p in the back head and leading to the supply reservoir Z.

During the operation of the parts so far described, the pressure fluid flowing from the throttle valve to the chamber b will be distributed to the ends of the piston chamber by

the valve *d*. The pressure fluid admitted through the inlet passage *e* into the rearward end of the cylinder will actuate the piston *E* forwardly to deliver its blow against the working implement *P* and the pressure fluid admitted into the front end of the piston chamber will actuate the piston *E* to the rearward end of the piston chamber.

During the rearward movement of the piston the flutes *H* in the extension *F* will be drawn into communication with the front end of the piston chamber and a portion of the pressure fluid acting against the forward surface of the piston will then flow through the flutes *H* and through the chuck *K* into the drill steel during each rearward stroke of the piston. This method is generally termed "puff-blowing" and in some instances the amount of pressure fluid thus admitted to the drill hole may be sufficient to maintain a fairly clean rock face. When drilling certain rock formations however, or when drilling holes of considerable depth the small amount of pressure fluid admitted into the drill hole in this manner is often found to be insufficient to properly cleanse the drill hole. Cuttings will then accumulate around the drill steel rearwardly of the cutting bit where they form a collar and tend to retard the action of the rotation mechanism. In view of these facts it is desirable that means be provided to enable the occasional introduction of a large volume of pressure fluid into the drill hole for effecting a thorough cleansing thereof whenever the conditions hereinbefore related occur.

Various means have heretofore been devised for accomplishing this result. In substantially all instances however, the bore through the chuck parts forms a part of the conduit for conveying the pressure fluid to the bore in the working implement. When the parts are still new this method may not present any serious objections but after some usage the parts become worn, particularly the bore *O* of the chuck which acts as a guide for the working implement. If then the pressure fluid is admitted into the chuck cavity a considerable portion thereof flows along the cooperating surfaces of the working implement and the chuck to the atmosphere without doing any useful work.

The present invention aims to assure a sealed connection between the source of pressure fluid supply and the working implement. To this end a tube *q* is disposed slidably in the back head *h*, the rifle bar *U* and piston *E*, and is provided at its forward end with a coniform surface *r* adapted to cooperate with a correspondingly formed seat *s* at the rearward end of the bore *Q* of the working implement to form a seal between the tube and the working implement. The rearward end of the tube *q* extends into a recess *t* in the back head *h* and carries a flange

u, the rearward end of which serves as a pressure area *v*, and the opposite end of the flange *u* as an end area *w* against which acts a spring *x* seated with its opposite end against the bottom of the recess *t*.

The recess *t* is provided with suitable threads *y* to receive a threaded plug *z* whereby the recess *t* may be sealed. As an additional function the plug *z* also acts as a guide for the flange *u* of the tube *q*. The plug is accordingly provided with a recess *2* into which the flange *u* slidably extends and said recess serves as a supply chamber through which the pressure fluid flows into the tube. Such pressure fluid is admitted into the supply chamber through ports *3* in the plug *z* communicating with the ports *o* in the throttle valve *j* through a passage *4* in the back head *h*.

In structures embodying the form of the invention illustrated in the drawing, wherein the tube is intended to be retracted by spring pressure instead of by pressure fluid, the inner end of the recess *t* may be vented to the atmosphere through a passage *5* in the back head to prevent the accumulation of such pressure fluid as may find its way beneath the flange *u*.

During the normal operation of the drill the throttle valve *j* will occupy the position in which the port *o* will be in registry with the passage *p*. Pressure fluid will then flow to the chamber *b* to be distributed to the ends of the piston chamber by the valve *d* for actuating the piston. During this operation a portion of the pressure fluid will flow from the front end of the piston chamber to the bore in the working implement in the manner heretofore described.

In the event that the pressure fluid flowing through the flutes *H* to the bore *Q* is found to be insufficient to effect a suitable cleansing of the drill hole the throttle valve *j* may be rotated to the position illustrated in the drawing in which the port *o* is moved into registry with the passage *4*. In this position of the throttle valve communication between its interior and the distributing element is cut off so that the piston *E* will then be idle.

Upon the admission of pressure fluid into the passage *4* such pressure fluid will flow through the ports *3* into the supply chamber *2* and, inasmuch that the combined areas of the ports *3* are greater than the bore in the tube *q*, the pressure fluid acting against the pressure area *v* will overcome the pressure exerted by the spring *x* and move the tube downwardly until the coniform surface *r* is pressed into sealing relationship with the seat *s* in the working implement.

Pressure fluid may then flow through the tube and through the working implement under full line pressure until the drill hole is cleansed. After this effect has been obtained the throttle valve *j* may be rotated to cut off the supply of pressure fluid to the

5 supply chamber 2 and the tube q will then be retracted by the spring α so that the forward end of the tube will be moved out of contact from the working implement P during the subsequent operation of the hammer piston E.

From the foregoing description it will be evident that the present invention contains many desirable advantages. A few of these 10 are that there will be no wastage whatsoever of pressure fluid during the blowing operation and, that by retracting the tube q after blowing has been effected, the tube will not be subjected to the abrading action of the 15 working implement during the normal operation of the drill. The tube will therefore be capable of rendering service for a prolonged period of time since, as is well known, it is at the forward end, that is, the part 20 which comes into contact with the working implement where the tube is usually first rendered unserviceable through wear.

I claim:

1. In a fluid actuated rock drill, the combination of a cylinder and a hammer piston 25 therein, a drill steel to receive the blows of the piston and having a bore, a back head having a recess; a tube for conveying pressure fluid from the recess to the bore and 30 extending into the recess, and a pressure area on the tube adapted to be exposed to pressure fluid for effecting movement of the tube toward the drill steel.

2. In a fluid actuated rock drill, the combination of a cylinder and a hammer piston 35 therein, a drill steel to receive the blows of the hammer piston and having a bore, a back head having a recess, a tube for conveying pressure fluid from the recess to the bore and 40 extending into the recess, a flange on the tube having opposed end areas, means for selectively exposing one end area to pressure fluid for effecting endwise movement of the tube in one direction, and a spring acting 45 against the other end area for effecting endwise movement of the tube in the opposite direction.

3. In a fluid actuated rock drill, the combination of a cylinder and a hammer piston 50 therein, a drill steel to receive the blows of the piston and having a bore, a back head having a recess, a tube for conveying pressure fluid from the recess to the bore and extending into the recess, a flange on the tube having 55 opposed end areas, means for supplying pressure fluid to the tube and for exposing one end area to pressure fluid for pressing the forward end of the tube against the drill steel, and a spring acting against the 60 other end area to normally hold the tube out of contact from the drill steel.

4. In a fluid actuated rock drill, the combination of a cylinder and a hammer piston 65 therein, a drill steel to receive the blows of the piston and having a bore, a back head

having a recess, a tube for conveying pressure fluid from the recess to the bore, a plug forming a closure for the recess and having a supply chamber therein, means for selectively admitting pressure fluid into the supply chamber and through the tube into the bore, a flange on the tube disposed in the supply chamber and having a pressure area at its rearward end exposed to pressure fluid for pressing the tube against the drill steel during the blowing period, and a spring acting against the forward end of the flange for retracting the tube upon the cut-off of pressure fluid to the supply chamber. 70

5. In a fluid actuated rock drill, the combination of a cylinder and a hammer piston therein, a drill steel to receive the blows of the piston and having a bore, means including a distributing valve for distributing pressure fluid to the cylinder, a back head having a recess, a tube slidable relatively to the cylinder and affording communication between the recess and the bore, a flange on the tube disposed in the recess and having a pressure area adapted to be exposed to pressure fluid in the recess for holding the tube against the drill steel, means for normally holding the tube in the retracted position, and means including a throttle valve for selectively supplying pressure fluid to the distributing valve 85 and to the recess. 90

6. In a fluid actuated rock drill, the combination of a cylinder and a hammer piston therein, a drill steel to receive the blows of the hammer piston and having a bore, a back head having a recess, a tube for conveying pressure fluid from the recess to the bore, a flange on the tube disposed in the recess, means acting against one end of the flange for normally holding the tube in retracted position, and means for selectively exposing the other end of the flange to pressure fluid for holding the forward end of the tube in sealing relation with the drill steel while simultaneously supplying pressure fluid to the bore. 100 105

7. In a fluid actuated rock drill, the combination of a cylinder and a hammer piston therein, a drill steel to receive the blows of the hammer piston and having a bore, a back head having a recess, a tube for conveying pressure fluid from the recess to the bore, a flange on the tube disposed in the recess, a spring acting against one end of the flange for normally holding the tube in retracted position, and means for selectively exposing the other end of the flange to pressure fluid for holding the forward end of the tube in sealing relation with the drill steel while simultaneously supplying pressure fluid to the bore. 110 115 120

8. In a fluid actuated rock drill, the combination of a cylinder and a hammer piston therein, a drill steel to receive the blows of the piston and having a bore, a back head having a recess, a tube for conveying pressure 125 130

fluid from the recess to the bore and extending into the recess, a pressure area on the tube adapted to be exposed to pressure fluid for pressing the forward end of the tube against the drill steel, a valve for selectively admitting pressure fluid to the cylinder for actuating the piston and to the pressure area for actuating the tube, and means for normally holding the tube out of contact from the drill steel.

9. In a fluid actuated rock drill, the combination of a cylinder and a hammer piston therein, a drill steel to receive the blows of the hammer piston and having a bore, a back head having a recess, a tube for conveying pressure fluid from the recess to the bore and extending into the recess, a pressure area on the tube, means for selectively admitting pressure fluid to said pressure area to effect end-wise movement of the tube in one direction, and means for effecting the reverse movement of the tube upon the cut-off of the admission of pressure fluid to said pressure area.

In testimony whereof I have signed this specification.
